SIGNAL SYSTEM FOR RAILWAYS

Paul P. Stoker, Wilkinsburg, Pa., assignor to
The Union Switch & Signal Company, Swiss-
vale, Pa., a corporation of Pennsylvania

Application August 14, 1931. Serial No. 556,983

16 Claims. (Cl. 246—21)

My invention relates to signal systems for rail-ways, and particularly to signal systems for single track railways whereon traffic is controlled from a central office.

5 I will describe one form of apparatus embody-ing my invention, and will then point out the novel features thereof in claims.

The accompanying Figs. 1 and 2 when taken together with Fig. 1 on the left constitute one 10 form of my invention when applied to a stretch of single track extending between two passing sidings designated by the reference characters PS and PS1. In describing my invention I shall speak of the right-hand end of each figure as east 15 and the left-hand end as west, and I shall speak of a train travelling from the left to the right as an eastbound train and one travelling from the right to the left as a westbound train.

The traffic rails 1 and 2 of the stretch of rail-20 way are divided into track sections by the cus-tomary insulated rail joints 3. Starting from the left these track sections are designated by the reference characters 4T, A4T, 2T, A2T, B2T, C2T, D2T, E2T and 4T.

25 Although it was stated above that Figs. 1 and 2 when taken together with Fig. 1 on the left dis-closes a form of my invention applied to a stretch of railway between two passing sidings, I shall at certain places in the description consider Fig. 1 30 to be placed at the right of Fig. 2 so that the track section 4T of Fig. 1 mates with the track section 4T of Fig. 2. When Fig. 1 is thus placed at the right of Fig. 2 there is disclosed a form 35 of the apparatus of my invention as applied to signals at the two opposite ends of a passing siding.

While in Figs. 1 and 2 a specific arrangement 40 of track sections is disclosed it will be understood that my invention is by no means limited to this one arrangement but that the traffic rails may be divided into track sections as best suited to the local conditions.

Each track section is equipped with a track 45 circuit here shown as the conventional direct current type wherein a battery 4 is connected to the rails at one end of the section and a direct current neutral relay is connected across the rails at the opposite end of the section.

The wayside signals R2 and R4 govern east-50 bound traffic while the signals L4 and L2 govern wes-bound traffic. These wayside signals may be of any standard type and are here designated as light signals. The top signal A of both R2 and L4 is an absolute signal capable of displaying either a clear indication or a stop indication, while the

lower signal B of R2 and L4 is a permissive signal capable of displaying either a permissive indica-tion or a stop indication. The entrance signals L2 and R4 are each three position signals capable of displaying clear, caution or stop. H1 and H3 60 are "take siding" signals and when displayed con-vey to the approaching train the information that that train is to enter the siding. These take siding signals may take different forms such for example as a short semaphore arm, or disk or a 65 distinctive light and as here disclosed each is to be a distinctive light. While no intermediate wayside signals are shown in Figs. 1 and 2 such signals may be used if it seems desirable to do so. 70

These wayside signals are to be jointly con-trolled by means of a remote control system and by track circuits responsive to traffic conditions of the track sections. The remote control system may be one of many schemes now in use; however, 75 a preferred system to which my invention is par-ticularly adapted is that disclosed and claimed in the United States application of Snavely, Miller and Tunell for Remote control systems, Serial No. 538,380, filed May 18, 1931. 80

The above remote control system constitutes a means by which signal systems can be manually controlled and operated from a remote or cen-tralized location. This remote control system carries out its remote control by codes designed 85 on the circuit sequence principle. The codes are given individual character by the sequence in which the control circuits are operated. A line channel consisting of three wires connects serially 90 from the central office equipment through each field station equipment. This three wire channel provides two independently operated series cir-cuits and one common return circuit. Since two 95 independent series circuits are provided the line action at any instant may be given any one of three characters dependent upon whether the first circuit, the second circuit or both circuits are operating. These three variables have been desig-nated respectively as "X", "Y" and "Z". Each code 100 action, either control or indication, consists of eight successive steps. Each step has a specific function and is identified by one of the three char-acters "X", "Y" or "Z". In the disclosure of this application only enough of the field apparatus of the remote control system is shown to clearly 105 illustrate a preferred manner whereby the appa-ratus of my invention may be governed by an operator located at a central office, and also to illustrate the manner whereby the wayside signals 110

may be made to govern a return indication to the central office.

In Figs. 1 and 2 the relays shown within the panels indicated by dash and dot lines are relays of the field line unit, the field storage unit and the field coding unit, respectively of the above-mentioned remote control system, and each of these relays is here given the same reference character that identifies the corresponding relay in the above-mentioned application Serial No. 538,380. For this description, it is deemed sufficient to say that the remote control system permits the operator at the central office to select, by sending the proper code, either one of the controlling relays 6XS or 6YS, and either one of the relays 7XS or 7YS of the storage unit at any one of the field stations along the railway. Also, that when one of these relays is selected it becomes energized to raise its armature into engagement with front contacts and that when once energized by a control code it is held energized by a stick circuit until its function is fully completed or until a new control code is transmitted by the operator. It is to be pointed out that while the relays 6XS and 6YS are ordinarily utilized to govern the operation of a local switch machine, I propose in this system to utilize these relays 6XS and 6YS at each location to control the take siding signal and the permissive signal as will be fully described later.

Relay SA of the field storage unit is the starting relay for the return indication, while relays 6V and 7V govern the energization of relay SA. Relays T6 and T7 are the sixth and seventh step chain group relays, respectively, while relays TX, TY and TZ of the field line unit are the transmitting relays for supplying to the line channel to the central office an X, Y or Z character. As the manner whereby these several relays of the remote control system function in connection with the apparatus associated with the return indication of the remote control system forms no part of my invention, the full operating circuits for the relays are omitted from the figures for the sake of clearness. It is deemed sufficient for this specification to point out that the indication code action is made up of eight successive steps and is started by the energizing of the relay SA of a field storage unit. Each step of an indication code action is distinguished by one of the three characters "X", "Y" or "Z", so that the indication code action at the central office is determined by the successive characters of the eight steps. Individual starting circuits for each signal function are arranged so that they become energized only on a change of status of the wayside signal equipment. Energy is cut off the starting circuit by a relay V of the field storage unit at the completion of the indication code action by the controlling relay V being energized or deenergized as the case may be to set up a disagreement between the relay SA and the wayside signal function. The character of the successive steps of an indication code is obtained by energizing one of the transmitting relays TX, TY or TZ of the field line unit. The manner whereby the wayside signal apparatus of my invention controls the starting circuits for the starting relay SA and controls the current for energizing the transmitting relays TX, TY and TZ will be fully described as the specification progresses.

Energy at each switch location D and E is obtained from a line transformer L the primary 5 of which is permanently connected to a transmission line designated by the line wires 6 and 7

which are constantly supplied with alternating current of any convenient frequency, such as 60 cycles per second, from a source not shown in the figures. The secondary 8 of the transformer L is connected to the terminals of a storage battery 9 through a full wave rectifier 10, and thus it follows that the storage battery 9 is trickle charged by current from the transmission line. The storage battery 9 supplies direct current at the proper voltage to the several operating and control circuits. The positive terminal of the battery 9 is designated in the figures by the reference character BL while the negative terminal is designated by the reference character CL.

The operating circuits for the entrance signals L2 and R4 are governed by direct current polarized relays L2H and R4H, respectively. L2HP and R4HP are slow releasing repeater relays associated with the polarized relays L2H and R4H respectively, and each is energized by a simple circuit that includes a front contact of the associated polarized relay as will be readily understood by an inspection of Figs. 1 and 2.

As the operating circuits of signals L2 and R4 are alike, a description of the circuits for one will suffice for an understanding of both. Referring to signal L2, its clear operating circuit starts from the positive terminal BL of the battery 9 and includes the front contact of the armature 11 of the repeater relay L2HP when it is energized in response to the energization of the relay L2H, front contact of the armature 12 of the polarized relay L2H when that relay is energized in a manner to be described later, right-hand contact of the polarized armature 13, wire 14, signal L2 and to the negative terminal CL. The caution operating circuit is the same as that just traced for the clear circuit up to the polarized armature 13, thence by the left-hand contact and wire 15 to the signal L2 and to the negative terminal CL. The stop operating circuit includes the back contact of the armature 11 of the repeater relay L2HP and wire 16 to the signal L2 and to the negative battery terminal CL.

The polarized relay L2H is controlled by means of a line circuit that is supplied with current at the opposite end of the passing siding PS1, at which point the apparatus will be the same in all respects as that disclosed in Fig. 2. Considering for the time being that Fig. 2 is placed at the left of Fig. 1 the control circuit for relay L2H can be traced from the positive terminal BL through the back contact of the armature 17 of a signal controlling relay LA4H of Fig. 2, wire 18, back contact of armature 19 of a despatcher controlled relay R4HS, wire 20, front contact of armature 21 of the track relay 4TR for the track section 4T, line wire 22, front contact of armature 23 of the track relay A4TR, front contact of armature 24 of a despatcher controlled relay L2HS when that relay is energized in a manner to be later pointed out, winding of the relay L2H, wire 25, back contact of armature 26 of a despatcher controlled relay 1HS, front contact of armature 27 of relay L2HS, front contact of armature 28 of the track relay A4TR, line wire 29, front contact of armature 30 of the track relay 4TR, wire 31, back contact of armature 32 of the relay R4HS, wire 33, back contact of armature 34 of relay LA4H and to the negative battery terminal CL. It will be observed that when the signal controlling relay LA4H for the signal in advance is energized so as to bring its armatures 17 and 34 into engagement with front contacts, the polarity of the current supplied to the above

80

85

90

135

140

145

traced line circuit is reversed. Thus, the polarized signal controlling relay L2H for the signal L2 is energized when the despatcher controlled relay L2HS is selected and the track sections between the signal L2 and the next signal in advance are unoccupied. The current supplied is of one polarity when the relay controlling the next signal in advance is energized to clear that signal and is of the reverse polarity when the relay for the signal in advance is deenergized.

In like manner the polarized relay R4H for the signal R4 is controlled by a polarized line circuit that receives current at the head block signal located at the opposite end of the siding.

Still considering Fig. 2 to be placed at the left of Fig. 1, the circuit for the relay R4H can be traced from the positive terminal BL through the back contact of armature 35 of the signal controlling relay RA2H associated with the signal R2, wire 33, back contact of armature 37, of the despatcher controlled relay L2HS, wire 38, front contact of armature 39 of the track relay A4TR, line circuit 40, front contact of armature 41 of the track relay 4TR, front contact of armature 42 of the despatcher controlled relay R4HS when that relay is energized, back contact of armature 43 of the relay 3HS, winding of relay R4H, front contact of armature 19 of the relay R4HS, wire 20, front contact of armature 21 of the relay 4TR, line wire 22, front contact of armature 23 of the relay A4TR, back contact of armature 24 of the relay L2HS, wire 44, back contact of armature 45 of the relay RA2H and to the negative terminal CL. Thus, the circuit for the signal controlling relay R4H is closed when the despatcher selects the relay R4HS and the track sections between the signal R4 and the next signal in advance are unoccupied. The current is of one polarity when relay RA2H is energized to clear the signal R2 and is of a reverse polarity when the relay RA2H is down and the signal R2 is at stop.

The circuit for the despatcher controlled relay L2HS that governs the signal controlling relay L2H is closed when the despatcher selects the relay 7XS of the field storage unit at the switch location D to thereby bring armature 47 into engagement with its front contact. This circuit for energizing the relay L2HS starts at the positive terminal BL at the armature 46 of the relay 7YS and includes the back contact of armature 48, front contact of armature 47 of relay 7XS, back contact of armature 43 of the relay R2HS, wire 49, winding of the relay L2HS and to the negative terminal of the battery 9. A similar circuit is provided for the despatcher controlled relay R4HS, which is closed when the despatcher selects the relay 7YS of the field storage unit at the switch location E to thereby bring its armature 52 into engagement with a front contact. Likewise the despatcher controlled relays R2HS and L4HS govern the signal controlling relays RA2H and L4HS, respectively. The circuit for the relay R2HS is closed at the front contact of armature 50 of the relay 7YS at the location D, while the circuit for the relay L4HS is closed at the front contact of armature 51 of the relay 7XS at the location E.

The absolute signal A of the head block signal L4 is governed by signal controlling relay LA4H, while the permissive signal B is governed by the relay LB4H. In similar manner the absolute signal A of the head block signal R2 is governed by the signal controlling relay RA2H and its permissive signal B is governed by the relay RB2H.

With Fig. 1 placed on the left of Fig. 2 so that signals L4 and R2 are opposing head block signals governing traffic in opposite directions through the stretch of track between the sidings PS and PS1, the relays RA2H and LA4H, which govern the opposing absolute signals RA2 and LA4, respectively, are controlled by a line circuit that is normally connected to battery at each end of the stretch. Starting at the switch D this line circuit can be traced from the positive battery terminal BL through the back contact of armature 53 of a stick relay R2S to be referred to later, back contact of armature 54 of the relay R2HS, wire 55, front contact of armature 56 of the track relay 2TR, line wire 57, front contacts of armatures 58 and 59 of the track relays A2TR and B2TR, respectively, line wire 60, front contacts of armatures 61 and 62 of the relays C2TR and D2TR, respectively, line wire 63, front contact of armature 64 of relay E2TR, wire 65, back contact of armature 66 of relay L4HS, and back contact of armature 67 of a stick relay L4S to the positive terminal BL at the switch location E. The other side of the line circuit is normally connected to the negative terminal CL at the switch location D from which it extends through the back contact of armature 68 of the relay R2HS and then through the following elements in succession 69, 70, 71, 72, 73, 74, 75, 76, 77, 78, 79, and the back contact of armature 80 of the relay L4HS to the negative battery terminal CL at the switch location E. It follows, therefore, that normally this line circuit is deenergized. With the despatcher transmitting a control code that energized the relay 7YS at the switch location D the relay R2HS is energized in turn to bring its armatures 54 and 68 into engagement with front contacts and out of engagement with their back contacts with the result that the above traced line circuit is disconnected from the battery at location D and is connected to the terminals of the signal governing relay RA2H by wires 115 and 116. Under this condition the relay RA2H is energized by current now supplied to the line circuit by the battery at the switch location E in the event the intervening track sections are unoccupied and each track relay picked up. With the relay RA2H thus energized the clear operating circuit to the absolute signal RA2 is closed at the front contact of the armature 81. In the event the despatcher sends a control code that selects the relay 7XS at the switch location E so that the despatcher controlled relay L4HS is picked up to thereby bring its armatures 66 and 80 into engagement with their front contacts and out of engagement with their back contacts, then the above-traced line circuit is disconnected from battery at the location E and the signal controlling relay LA4H is connected thereto. This results in relay LA4H being energized by current supplied to the line circuit at the location D if the intervening track sections are unoccupied. With relay LA4H energized the clear operating circuit to the absolute signal A of L4 is closed at the front contact of the armature 82. It follows from the above discussion of the line circuit that only one of the opposing signal controlling relays LA4H and RA2H can be energized at a time and that the control line circuit is controlled by a despatcher controlled relay and by the track relay of each track section between the two opposing signals.

Associated with the relays RA2H and LA4H are the stick relays R2S and L4S, respectively. Referring to the relay R2S, we find that it is pro-

vided with an energizing circuit that starts at the positive battery terminal BL and includes a back contact of armature 83 of the track relay 2TR, front contact of armature 84 of the signal controlling relay RA2H when that relay is energized, winding of relay R2S and to the negative battery terminal CL. The stick circuit for the relay R2S starts from the positive battery terminal BL and includes the front contact of armature 85 of the despatcher controlled relay R2HS, back contact of armature 86 of relay RA2H, front contact of its own armature 87, winding of the relay R2S and to the negative battery terminal CL. Thus, with a train entering the track section 2T and shunting the track relay 2TR at a time when the signal controlling relay RA2H is energized the stick relay R2S is picked up and then held up inasmuch as the front contact of armature 84 of relay RA2H is retained closed for a time interval after the track relay 2TR is shunted due to the slow releasing characteristics with which relay RA2H is provided, and due to relay R2S being made slightly slow acting so as not to release its contacts between the opening of front contact 84 and the closing of back contact 88 of relay R2AH as that relay releases. As the circuits for the stick relay L4S are similar to those for the relay R2S, it seems unnecessary to describe them in detail.

The permissive signal B of R2 has its operating circuits governed by the armature 88 of the relay RB2H in such a manner that when the relay is energized and armature 88 brought into engagement with its front contact the permissive signal is displayed while when the relay is deenergized and the armature 88 engages its back contact the stop signal is displayed. In a like manner the operating circuits to the signal B of L4 are controlled by the armature 89 of the signal controlling relay LB4H.

Although the switches D and E, as well as all switches of my system, are preferably hand-thrown, at each switch, however, there is provided a take siding signal by means of which the despatcher can issue instructions to a train that he wishes that train to take the siding and clear the main track. As the switch is hand-thrown, I propose to utilize the usual switch control relays 6XS and 6YS of the field storage unit of the remote control system for controlling the operation of the take siding signal and to control the operation of the permissive signal located at the same point. It is understood that when the despatcher desires to clear one of the signals controlled by the relays 6XS and 6YS he does so by transmitting a control code in the usual manner. For example, if a despatcher desired to have the take siding signal H1 displayed he would transmit a control code that selects the relay 6YS at location D. When relay 6YS picks up the circuit to the relay 1HS is closed at the front contact of the armature 92, and when relay 1HS picks up the operating circuit to the signal H1 is closed at the front contact of the armature 93. As the relay 6YS is selected by the control code transmitted from the central office a stick circuit is closed for that relay which extends from the positive terminal BL through a circuit controller 105 operated by the switch D and opened when the switch is thrown for traffic to the siding, wire 106, resistance 107, contact C1 operated by the apparatus of the storage unit, back contact of armature 108 of the relay 6XS, front contact of armature 109 of relay 6YS, winding of relay 6YS and to the negative terminal CL through the usual control

circuit of the storage unit. It follows then that as the train crew operates the switch D after having been instructed to take the siding by the display of the signal H1, the relay 6YS is deenergized and the signal H1 immediately returned to its non-active position, it being understood that the energizing circuit for relay 6YS through the apparatus of the remote control system was opened at the completion of the control code. At the switch E the take siding signal H3 is controlled by the relay 6YS of the storage unit at that location in a like manner.

In the event the despatcher at the central office desires to permit a second eastbound train to follow a first eastbound train from the location D, he would do so by sending a control code that selects the relay 6XS at location D, it being understood that the relay R2HS is now energized as the result of the control code that cleared the signal RA2 for the first train and that the stick relay R2S is held energized by its stick circuit. When relay 6XS is selected a circuit is closed from the positive battery terminal BL through the back contact of armature 104 of the relay 6YS, front contact of armature 90 of relay 6XS, front contact of armature 91 of the stick relay R2S, winding of the relay RB2H and to the negative terminal CL. The energization of the relay RB2H effects the closing of the operating circuit for clearing the permissive signal B of R2. The permissive signal B of L4 controls following train movements west from the siding PS and is itself controlled by the relay 6XS of the storage unit at the location E in a manner similar to that described for the signal B of R2.

As previously mentioned, the remote control system provides a return indication from the wayside apparatus to the central office indicating that the function desired has been completed by the wayside equipment. In the system as disclosed in the above-mentioned application, Serial No. 538,380 the indication code action is accomplished in eight steps, and as previously stated, each step consists of an X, Y or Z character. These X, Y and Z characters are transmitted to the line channel by means of the relays TX, TY and TZ of the field line unit at each field station. The starting of the indication code is controlled by means of the starting relay SA of the field storage unit. In Figs. 1 and 2, I have shown a preferred manner whereby the wayside equipment of my invention may control the operation of these relays associated with the indication code of the above-mentioned remote control system.

Current for energizing the starting relay SA of the field storage unit may be supplied by any one of several parallel starting circuits which are governed by the condition of the wayside signal equipment and which are energized upon a change of status of the signal equipment. Referring to Fig. 1, when the relay L2HP is picked up to clear the signal L2, a starting circuit is closed from positive battery terminal BL through the front contact of armature 94 of relay L2HP, wire 95, and a front contact C3 of the relay 7V of the storage unit to the starting relay SA. When the relay RA2H is picked up to clear the signal RA2, a starting circuit is closed from positive battery terminal BL through the back contact of the armature 94 of relay L2HP, wire 96, front contact of armature 97 of relay RA2H and the front contact C3 of the relay 7V to the starting relay SA. When both relays L2HP and RA2H are down

80

150

indicating that both signals L2 and R2 are set at stop, a starting circuit is closed from positive terminal BL through the back contact of the armature 94, wire 96, back contact of the armature 97 and the back contact C3 of the relay 7V to the starting relay SA. If relay RB2H be energized to clear the permissive signal RB2 a starting circuit is closed from positive terminal BL through the front contact of the armature 110, wires 111 and 99 and the front contact C3 of a relay 6V to the starting relay SA. In the event the relay 1HS is energized to select the take siding signal H1, a starting circuit is closed from the positive terminal of the battery 9 through the front contact of armature 98 of relay 1HS, wire 99 and the front contact C3 of relay 6V to the starting relay SA. Again, when the relay 1HS is deenergized to open the operating circuit to a signal H1, a starting circuit is closed from the positive terminal of the battery line through the back contact of armature 98 and the back contact C3 of the relay 6V to the starting relay SA. It is to be seen, therefore, that when a signal controlling relay takes a position to either clear a signal or to set a signal at stop a starting circuit is established to the starting relay SA of the remote control system.

The individual X, Y and Z characters of the sixth and seventh step of the indication code are selected by the various signal relays of my system in the following manner: When the chain group relay T6 of the field coding unit is picked up during the sixth step of the indication code action, current is supplied from the positive battery terminal BL through the front contact A5 of relay T6 to the armature 112 of relay RB2H and thence through the front contact of that armature if relay RB2H has been energized to clear signal RB2, and wire 113 to the winding of the transmitting relay TX of the field line unit to thereby transmit an "X" code character. If relay RB2H is deenergized then a circuit extends through the back contact of armature 112 along wire 114 to the armature 100 of relay 1HS and thence through its front contact if relay 1HS is energized to clear signal H1, to the winding of the transmitting relay TY to transmit a "Y" character. In the event both relays RB2H and 1HS are deenergized the circuit is completed from the armature 100 through its back contact to the winding of the transmitting relay TZ to thereby transmit a "Z" character.

During the seventh step of the indication code action when the chain relay T7 is energized a circuit is closed from the positive battery terminal BL through the front contact A5 of relay T7 to the armature 101 of the relay L2HP, thence through the front contact of that armature if relay L2HP is energized to clear the signal L2 to the winding of the transmitting relay TX to thereby transmit an "X" character during the seventh step of the indication code. With relay L2HP down, the armature 101 engages its back contact and the above circuit from A5 of relay T7 extends by wire 102 to the armature 103 of the relay RA2H, thence by the front contact of that armature if relay RA2H is energized to clear the signal RA2 to the transmitting relay TY to transmit a "Y" character during the seventh step of the indication code. In the event the relay RA2H is deenergized and the armature 103 is in engagement with its back contact the circuit is completed to the transmitting relay TZ

to transmit a "Z" character during the seventh step of the indication code. Thus, not only are the starting circuits to the starting relay SA governed by the different signal controlling relays but the signal controlling relays also govern the circuits for energizing the different transmitting relays to determine the code character to be transmitted to the central office during the sixth and seventh steps of the indication code action.

In describing the operation of my system I shall assume that an eastbound train occupies the track section A4T and that the remaining track sections are all unoccupied. In order to clear the signal RA2 so as to advance this eastbound train the despatcher transmits a control code that selects the relay 7YS at the location D and as this relay is energized the relay R2HS is in turn energized. When the relay R2HS picks up, the line control circuit is disconnected from battery at the location D and the signal controlling relay RA2H is connected thereto so that that relay is now governed by current supplied to the line control circuit at the switch location E. As the signal controlling relay RA2H becomes energized the clear operating circuit for the signal RA2 is closed at the front contact of the armature 81. Also, a starting circuit to the starting relay SA is closed at the front contact of the armature 97, and during the seventh step of the return indication code the circuit to the transmitting relay TY is completed at the front contact of the armature 103. As the train advances east past the clear signal RA2 it shunts the track relay 2TR to open the control line circuit at armatures 56 and 70 of the track relay 2TR to thereby deenergize the signal controlling relay RA2H to set the signal RA2 at stop. As the track relay 2TR is shunted, the energizing circuit to the stick relay R2S is closed during the release period of the relay RA2H and once the stick relay R2S is picked up, it is held energized by its stick circuit until the relay R2HS is deenergized by a control code or until the relay RA2H is again picked up due to the train passing beyond the limits of the track sections controlling the line control circuit. In the event a second eastbound train desires to follow the first eastbound train leaving the siding PS1 the despatcher transmits a control code that selects the relay 6XS at the switch location D to close the circuit that includes the front contacts of the armatures 90 and 91 of relays 6XS and R2S, respectively, to thereby energize relay RB2H. As the relay RB2H becomes energized the operating circuit is closed for clearing the permissive signal RB2 to thereby permit the second eastbound train to follow the first train without waiting for the first train to clear the track sections up to siding PS.

If any of the track sections between the two passing sidings is occupied by a westbound train, it is apparent that the relay RA2H will not be energized even should the despatcher select the relay R2HS by sending a code that selects the relay 7YS at location D. Furthermore, the despatcher cannot select the permissive signal RB2 for an eastbound train if there is a westbound train occupying any of the track sections due to the fact that the stick relay R2S is deenergized in this case and the circuit to the relay RB2H held open at the front contact of the armature 91.

Let us now assume that a westbound train has been advanced west from the siding PS by the despatcher clearing the signal LA4 in a manner similar to that described in connection with the signal R2. If the despatcher desires to advance

the westbound train past the signal L2 on the main track he transmits a control code that selects the relay 7XS at the location D to thereby energize the relay L2HS. As relay L2HS picks up the signal controlling relay L2H is connected to the line control circuit extending west from the location D. If the intervening track sections to the west end of siding PS1 are unoccupied the relay L2H becomes energized and its polarized armature 13 takes the right-hand position to close the clear operating circuit to signal L2 if the signal controlling relay for the westbound signal at the west end of the siding PS1 is energized and the current supplied to the line control circuit of normal polarity. In the event the signal controlling relay at the west end of the siding PS1 is de-energized and its signal is at stop then the polarity of the current supplied to the control line circuit leading to the relay L2H is such that polarized armature 13 assumes a left-hand position to close the caution operating circuit of signal L2. As relay L2H becomes energized, a circuit is completed to the repeater relay L2HP and that relay is energized and the connection from positive battery terminal to the operating circuits for signal L2 is closed. The energization of the relay L2HP also completes a starting circuit to the starting relay SA at the front contact of its armature 94, and closes the circuit leading to the transmitting relay TX at front contact of its armature 101.

Should the operator desire the westbound train to enter the siding PS1, he transmits a control code that selects relay 6YS at the location D so that the relay 1HS is energized to close the operating circuit to the take siding signal H1. As relay 1HS picks up, a starting circuit to the starting relay SA is closed at the front contact of its armature 98, and the circuit to the transmitting relay TY is closed at the front contact of its armature 100. The control and operation of the signals L4 and R4 are similar in every respect to those described for the signals R2 and L2.

A signal system such as here disclosed gives absolute protection for opposing traffic movements, allows for following movements and provides a convenient means for instructing trains to take a siding at meeting points. This signal system requires but two control line wires between siding locations and three line wires between opposite ends of sidings and is much simpler and less expensive to install than systems of this character heretofore proposed.

Although I have shown my invention applied to a specific remote control system it will be understood that it can be as well applied to other remote control systems such for example as the time code type.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway over which traffic normally moves in either direction, an absolute signal and a permissive signal located at each end of the stretch to control traffic in opposite directions through the stretch, a line control circuit, a signal controlling relay at each end of the stretch controlled by said line circuit to control the absolute signal at its end of the stretch but normally disconnected, despatcher

controlled means to at times connect one or the other of said signal controlling relays to said line circuit to clear an absolute signal, a directional relay at each end of the stretch energized in response to a train entering the stretch at the same end as the directional relay at a time when the associated signal controlling relay is energized, and other despatcher controlled means to clear a permissive signal when the directional relay is energized.

2. In combination, a stretch of railway over which traffic normally moves in either direction arranged in track sections, a track circuit for each track section responsive to traffic conditions of the section, an absolute signal and a permissive signal located at each end of the stretch to control traffic in opposite directions through the stretch, a line control circuit controlled by the track circuit of each section, a signal controlling relay for each absolute signal controlled by said line circuit but normally disconnected, despatcher controlled means to at times connect one or the other of said signal controlling relays to said line circuit to clear an absolute signal, a directional relay at each end of the stretch energized in response to a train entering the stretch at its respective end of the stretch at a time when the associated signal controlling relay is energized, and other despatcher controlled means to clear a permissive signal when the directional relay is energized.

3. In combination, a stretch of railway over which traffic normally moves in either direction arranged in track sections, a track circuit for each track section responsive to traffic conditions of the section, a line circuit controlled by the track circuit of each track section and normally connected to a current source at each end of the stretch, a signal controlling relay at each end of the stretch controlled by said line circuit but normally disconnected, despatcher controlled means to disconnect at times the current source at either end of the stretch and to connect the signal controlling relay located at the same end as the disconnected source to the line circuit to thereby energize said relay under clear traffic conditions of the track sections, an absolute signal at each end of the stretch cleared when the corresponding signal controlling relay is energized, a stick relay associated with each signal controlling relay energized in response to a train entering the track section adjacent its end of the stretch at a time when the associated signal controlling relay is energized, a permissive signal at each end of the stretch, and another despatcher controlled means effective to clear the permissive signal located at the end at which the stick relay is energized.

4. In combination, a railway having a main track and a passing siding, a track circuit for the main track, a signal to govern traffic over the main track, a take siding signal to instruct a train approaching said siding, a first despatcher controlled relay, a first signal controlling relay to control the signal for the main track jointly controlled by the track circuit and the first despatcher controlled relay, a second despatcher controlled relay, a second signal controlling relay controlled by the said second despatcher controlled relay to control the take siding signal, a circuit means rendered active when the first signal controlling relay functions to clear its associated signal to initiate a return indication, and another circuit means rendered active when the second signal controlling relay functions to clear

- the take siding signal to also initiate a return indication.
5. In combination, a railway having a main track and a passing siding, a track circuit for the main track, a signal to govern traffic over the main track, a take siding signal to instruct a train to take said siding, a first despatcher controlled relay, first signal controlling relay to control the signal for the main track jointly controlled by the track circuit and the first despatcher controlled relay, a second despatcher controlled relay, a second signal controlling relay controlled by the said second despatcher controlled relay to control the take siding signal, a starting circuit means rendered active when either of said signal controlling relays functions to clear its associated signal to initiate a return indication, and another circuit means rendered active when either of said signal controlling relays functions to clear its associated signal to determine the character of the return indication.
6. In combination, a railway having a stretch of single track connected by a track switch to a stretch of main track and a passing siding adjacent thereto, a main signal to govern the movement of traffic from the single track to the main track, a take siding signal to govern the movement of traffic from the single track to the passing siding, a first despatcher controlled relay, a first signal controlling relay controlled by the first despatcher controlled relay to clear the main signal to instruct a train to enter the main track, a second despatcher controlled relay, a second signal controlling relay controlled by the second despatcher controlled relay to set the take siding signal to instruct a train to enter the siding, and means to prevent the first despatcher controlled relay from controlling the said first signal controlling relay when said second signal controlling relay is energized to set the take siding signal.
7. In combination, a stretch of railway, an eastbound signal at each end of the stretch, a polarized relay to control the operation of the signal at the west end of said stretch, a neutral relay to control the operation of the signal at the east end of the stretch, a despatcher controlled relay at the west end of the stretch to control the energization of the said polarized relay, and a despatcher controlled relay at the east end of the stretch to control the energization of the neutral relay and to control the polarity of the current energizing the said polarized relay at the west end of the stretch.
8. A signal system for railways over which traffic normally moves in either direction including an absolute signal and a permissive signal at each end of a stretch of said railway to govern traffic in opposite directions through the stretch, a line circuit for said stretch adapted to be active for either direction of traffic, despatcher controlled means to select the direction for which said line circuit is to be active, a relay associated with each absolute signal arranged to be controlled by the line circuit when it is rendered active for the same direction of traffic as that governed by the associated absolute signal, a relay for each permissive signal, other despatcher controlled means to energize the last-mentioned relays but normally ineffective, and means to render the said other despatcher controlled means effective to energize the relay for the permissive signal governing traffic in the same direction as that with which the first mentioned despatcher controlled means has rendered the line circuit active.
9. A signal system for railways over which traffic normally moves in either direction and arranged in track sections including a track circuit for each track section responsive to traffic conditions of the section, an absolute signal and a permissive signal at each end of a stretch of said railway to govern traffic in opposite direction through the stretch, a line circuit for said stretch adapted to be active for either direction of traffic, despatcher controlled means to select the direction for which said line circuit is to be active, a relay associated with each absolute signal arranged to be controlled by the line circuit when it is rendered active for the same direction as that governed by the associated absolute signal, a relay for each permissive signal, other despatcher controlled means to energize the last-mentioned relays but normally ineffective, means to render the said other despatcher controlled means effective to energize the relay for the permissive signal governing traffic in the same direction as that with which the first mentioned despatcher controlled means has rendered the line circuit active, and means controlled by the track circuits of the sections for said stretch to control the line circuit when it is rendered active for either direction of traffic.
10. A signal system for railways including a stretch of track arranged in track sections, a track circuit for each track section responsive to traffic conditions of the section, an absolute signal and a permissive signal to govern traffic through the stretch, a line circuit, a signal controlling relay, a first despatcher controlled relay to render the line circuit active to energize said signal controlling relay for clearing the absolute signal, means controlled by each track circuit to control said line circuit adapted to prevent the energization of said signal controlling relay when a track section is occupied, a second signal controlling relay, a second despatcher controlled relay, a circuit controlled by the second despatcher controlled relay to energize the second signal controlling relay for clearing the permissive signal, and means to prevent the energization of the second signal controlling relay unless the first signal controlling relay has been energized and a train entered the first track section in advance of said signals.
11. In combination, an eastbound signal having a clear and a permissive indication, a westbound signal having a clear and a take siding indication, a first remote controlled means adapted to cause either one or the other of said signals to display a clear indication, a second remote controlled means adapted to cause either the eastbound signal to display a permissive indication or the westbound signal to display the take siding indication, and track circuit means responsive to traffic conditions to render at times the said first remote controlled means ineffective to cause a clear indication and at all other times to govern the control of the said second remote controlled means over the permissive indication of the eastbound signal.
12. In combination, a main track and a passing siding, a first signal having a clear and a permissive indication to govern traffic moving away from said siding, a second signal having a clear and a take siding indication to govern traffic moving towards said siding, a first despatcher controlled means to control the clear indication of each of said signals, a second despatcher controlled means to control the permissive indication of the first signal and the take siding indica-

tion of the second signal, and track circuit means to govern the control of the first despatcher controlled means over the clear indication of said signals and to govern the control of the second despatcher controlled means over the permissive indication of the first signal but not over the take siding indication of the second signal.

13. In combination, a stretch of railway over which traffic normally moves in either direction arranged in track sections, a track circuit for each track section responsive to traffic conditions of the section, a line circuit controlled by the track circuit of each track section and normally connected to a current source at each end of the stretch, a signal controlling relay at each end of the stretch controlled by said line circuit but normally disconnected, despatcher controlled means to disconnect at times the current source at either end of the stretch and to connect the signal controlling relay located at the same end as the disconnected source to the line circuit to thereby energize said relay under clear traffic conditions of the track sections, an absolute signal at each end of the stretch cleared when the signal controlling relay at the same end of the stretch is energized, a directional relay associated with each signal controlling relay energized in response to a train entering the stretch at its end of the stretch at a time when the associated signal controlling relay is energized, and other despatcher controlled means to clear a permissive signal when the directional relay is energized.

14. In combination, a stretch of railway, an absolute signal and a permissive signal to govern traffic over the stretch, a first signal controlling relay to govern the operation of the absolute signal, a second signal controlling relay to govern the operation of the permissive signal, a starting circuit means rendered active when either of said

signal controlling relays functions to operate its signal to initiate a return indication, and another circuit means rendered active when either signal controlling relay functions to operate its signal to determine the character of the return indication in accordance with the relay that functions.

15. In combination, a stretch of railway, an absolute signal and a permissive signal to govern traffic over the stretch, a first signal controlling relay to govern the operation of the absolute signal, a second signal controlling relay to govern the operation of the permissive signal, a starting circuit means rendered active when either of said signal controlling relays functions to operate its signal to initiate a return indication, another circuit means rendered active when either signal controlling relay functions to operate its signal to determine the character of the return indication in accordance with the relay that functions, and traffic controlled means to prevent the second signal controlling relay from functioning unless the first signal controlling relay has previously functioned.

16. In combination, a railway having a main track and a passing siding, a switch leading from the main track to the passing siding, a take siding signal normally inactive, a despatcher controlled relay adapted when energized to render said take siding signal active, a stick circuit for retaining said relay energized and arranged to be closed only when said switch is set for the main track, an indication circuit associated with said relay, and means effective to open said stick circuit when said switch is set for the siding whereby said relay is deenergized to restore the signal to its normal inactive condition and to render the indication circuit active.
